CIRCUIT BREAKER

Francis L. Gelzheiser, Pittsburgh, and Joseph A. Drobney, Beaver, Pa., assignors to Westinghouse Electric Corporation, East Pittsburgh, Pa., a corporation of Pennsylvania

Application September 11, 1951, Serial No. 246,082

12 Claims. (Cl. 209—116)

1

This invention relates to circuit breakers and more particularly to circuit breakers which are manually operable to open and close the circuit and which are automatically operated to open the circuit in response to overload currents.

An object of the invention is to provide a circuit breaker which is manually operable to open and close the circuit and automatically operated in response to overload currents to open the circuit, with novel means for giving an indication that the breaker has been automatically opened.

Another object of the invention is to provide a circuit breaker having switch means that is operated only in response to automatic opening of the breaker to effect an indication of the condition of the breaker.

Another object of the invention is to provide a circuit breaker with means of simple construction and reliable in operation for signalling when the circuit breaker has been automatically tripped open.

The novel features that are considered characteristic of the invention are set forth in particular in the appended claims. The invention itself, however, both as to structure and operation, together with additional objects and advantages thereof will be best understood from the following detailed description thereof when read in conjunction with the accompanying drawing.

In said drawing:

Figure 1 is a vertical sectional view of a circuit breaker embodying the principles of the invention.

Fig. 2 is an enlarged horizontal sectional view taken substantially on line II—II of Fig. 1 showing the signal switch and the operating means therefor.

Fig. 3 is a vertical end view of the breaker with the cover partly broken away to more clearly illustrate the signal switch and the operating means therefor.

Referring to Fig. 1 of the drawing, the circuit breaker illustrated comprises, in general, a housing comprising a recessed base 11 of molded insulating material and a cooperating cover 13 also of molded insulating material, a stationary contact 15, a pivoted switch member 17 carrying a movable contact 19 for cooperating with the stationary contact, operating means indicated generally at 21 and a trip device indicated generally at 23.

The stationary contact 15 is mounted on the inner end of a conducting strip 25 which extends outwardly through an opening in the base 11 and has a connecting means 27 on its outer end.

2

The operating mechanism 21 and the pivoted switch member 17 are supported in a U-shaped main frame 29 suitably secured to the base 11.

The switch member 17, which carries the movable contact 19, comprises a resilient strip secured at its other end to a support member 31 pivotally mounted on a pin 33 supported in the side members of the main frame 29.

The operating mechanism 21 for the circuit breaker comprises a toggle consisting of a pair of toggle links 35 and 37, a pivoted carrier 39, an overcenter spring 41 and a U-shaped operating lever 43. The toggle links 35 and 37 are pivotally connected by a knee pin 45 and the toggle link 35 is pivotally connected to the carrier 39 by a pivot pin 47. The toggle link 37 is pivotally connected by means of a pivot pin 49 to the support member 31. The overcenter spring 41 is connected at its lower end to the knee pivot pin 45 of the toggle 35—37 and at its outer end to the yoke portion of the U-shaped operating lever 43. The legs of the operating lever 43 are pivoted on projections 51 formed outwardly from the sides of the main frame 29. Ears 53 formed outwardly from the main frame 29 serve to limit the movement of the operating lever 43. An operating handle 55 of molded insulating material is mounted on the outer end of the operating lever 43 and projects through an opening 57 in the cover 13. An arcuate portion 59 of the handle serves to substantially close the opening 57 in all positions of the operating lever 43.

The carrier 39 is pivotally mounted on a pivot pin 61 supported in the main frame 29 and is normally releasably restrained in operative position by the trip device 23.

The circuit breaker is opened manually by counterclockwise movement of the handle 55 and the operating lever 43 which carries the line of action of the overcenter springs 41 over to the left of the pivot pin 47. This action causes collapse of the toggle 35—37 and opening movement of the switch member 17. Clockwise movement of the handle 55 and the operating lever 43 back to the position shown moves the line of action of the overcenter springs 41 across to the right of the pivot pin 47 whereupon the toggle 35—37 is straightened and the switch member 17 is actuated to close the contacts.

The trip device 23 comprises a bimetal element 63 having an armature 65 mounted thereon and a fixed magnetic member 67. The bimetal element 63 and the magnetic member 67 have mounting feet formed thereon and are rigidly secured to the base 11 by means of a screw 69. One

end of the bimetal element 63 is connected by means of a flexible conductor 71 to the switch member 17 and the other end of the bimetal element 63 is connected by means of a flexible conductor 73 to a conducting strip 75 which extends outwardly through an opening in the end wall of the base 11 and has a terminal connecting means 77 mounted on its outer end. An adjusting screw 79 threaded into the upper end of the bimetal element 63 has a latch portion 81 which is engaged by a latch member 83 on the carrier 39, in order to releasably restrain the carrier in operative position.

When an overload current below a predetermined value of, for instance, ten times normal rated current occurs the bimetal element 63 becomes heated, and when heated, a predetermined amount bends toward the left releasing the carrier 39. When released the carrier 39 rotates clockwise about its pivot 61 under the influence of the overcenter springs 41 and carries the pivot 41 across to the right of the line of action of the overcenter springs. This causes collapse of the toggle 35-37 and opening movement of the switch member 17.

Following an automatic opening operation, the carrier 39 is reset and relatched by movement of the handle 55 to the "off" position. During this movement a projection 85 on the operating lever 43 engages and moves the carrier 39 counterclockwise. This movement causes the latch member 83 to wipe by the latch 81 slightly flexing the bimetal 63 which thereafter resumes its normal position with the latch 81 in latching engagement with the latch member 83. The circuit breaker is then closed in the previously described manner by movement of the handle 55 to the "on" position.

Upon the occurrence of an overload current of ten times or more of normal rated current or a short circuit current, the electroresponsive means 65-67 is energized sufficiently by the current flowing through the bimetal element 63 and moves the armature 65 toward the fixed magnetic member 67 bending the bimetal element and causing instantaneous release of the carrier 39 and opening of the breaker.

Means is provided for effecting a signal when the circuit breaker is automatically tripped open. The signalling means, indicated generally at 67 (Fig. 2), is not operated when the breaker is manually opened. The signal means is enclosed in a separate casing 89 of insulating material and comprises a stationary contact 91 mounted on a conducting strip 93 and a cooperating movable contact 95 mounted on a resilient switch arm 97. The conducting strip 93 is secured to the casing 89 by a rivet 99 which also secures a terminal 101 to the outside of the housing. One end of the resilient switch arm 97 is secured to the casing 89 by a rivet 103 and this rivet also secures a terminal 105 to the outside of the casing 89. The bias of the resilient arm 97 is such so as to bias the contact 95 closed against contact 91. The terminals 101 and 105 serve to connect the signal switch in an electric circuit to energize a signalling device (not shown) which may be either a visible or audible device. The signal switch casing 89 is removably mounted on the outside of the cover 13 of the circuit breaker by means of a strip 107, the ends of which are removably fastened to the cover by screws 109 (Fig. 3) which are threaded into the cover 13.

The signal switch contacts 91-95 are normally held in open position against their bias by means

5 of an actuating spring 111. The spring 111 has a portion 113 extending at right angles (Fig. 1) to the main body of the spring by which the actuating spring is mounted on the inside surface of the cover 13 and secured thereto by screws 115 and nuts 117. The spring 111 also has an actuating portion 119 formed substantially at right angles to the main portion 111 and extending transversely across the breaker operating mechanism adjacent the carrier 39 to be actuated by the carrier.

10 Disposed between the main body of the spring 111 and the resilient switch arm 97 of the signal switch is a pair of plungers 121 and 123. The plunger 121 extends through an opening in the cover 13 and has a flange 125 thereon which is disposed in a counterbore in the outside of the cover 13. The plunger 123 extends through an opening in the wall of the casing 89 adjacent the cover 13 and is disposed between the plunger 121 and the resilient switch arm 97. The flange 125 cooperates with the cover 13 of the circuit breaker and with the casing 89 of the signal switch to form a tortuous path substantially preventing the passage of hot gases from the interior of the circuit breaker to the interior of the signal switch.

15 The actuator spring 111 is stronger than the resilient switch arm 97 and its initial tension is sufficient to normally maintain the resilient switch arm 97 in the open position through the agency of the plungers 121 and 123. In the closed position of the breaker the parts are in the positions shown in full lines in Figs. 1 and 2. When 20 the circuit breaker is tripped open in response to an overload current and the carrier 39 rotates in a clockwise direction (Fig. 1) to effect opening of the breaker contacts, a surface 127 on the carrier 39 engages the portion 119 of the actuating spring 111 and bends the spring 111 to substantially the position shown by dot and dash lines at 119a (Fig. 2). This further stresses the spring and moves the main body 111 thereof away from the plunger 121 whereupon the tension of 25 the resilient switch arm 97 acts to close the signal switch contacts 91-95 and effect energization of the signal circuit.

30 When the carrier 39 is rotated counterclockwise by manipulation of the handle to reset the mechanism, as previously described, the surface 127 moves away from the portion 119 of the spring 111 and the resilience of the spring 111 causes it to resume its normal position. At this time the spring 111 acts through the plungers 121-123 to 35 overcome the tension of the resilient switch arm 97 and open the signal switch contacts 91-95.

35 The signal switch is not operated on manual opening of the circuit breaker since on such operations the carrier 39 is not released, hence, the signal switch functions to give a signal only on 40 automatic opening of the breaker.

45 It is a very desirable feature of the invention that both the switch unit 87 and the actuating spring 111 are mounted solely on the cover 13 of the breaker. This is important from a manufacturing standpoint since no modification of the breaker mechanism or of the base 11 is required, it only being necessary to mount on the base 11 carrying the breaker mechanism, a cover 13 having the switch unit 87 and the actuating spring 111 thereon. After the cover 13 is mounted on the base 11, the housing is sealed in a well known manner to prevent tampering with the breaker.

50 It will be seen that the invention provides a circuit breaker having a signal switch that is

operated by the breaker mechanism only on automatic tripping operations. The signal switch is of simple construction having few parts, is reliable in operation and inexpensive to manufacture. The signal switch itself is removably mounted on the outside of the breaker housing to permit removal and replacement thereof without disturbing the seal of the breaker housing and without disturbing the calibration of the circuit breaker.

While the invention has been disclosed in accordance with the provisions of the patent statutes, it is to be understood that various changes and modifications may be made in the structural details and combination of elements disclosed without departing from some of the essential features of the invention.

We claim as our invention:

1. A circuit breaker comprising an enclosing housing, operating means releasable to cause automatic opening of said breaker and trip means responsive to overload currents for effecting release of said releasable operating means and automatic opening of said breaker, auxiliary switch means mounted on the outside of said enclosing housing, and actuating means for said auxiliary switch means mounted on the inside of said housing and engageable by said releasable operating means to effect operation of said auxiliary switch means.

2. A circuit breaker comprising an enclosing housing of molded insulating material, means releasable to effect automatic opening of said breaker, a trip device responsive to abnormal circuit conditions for releasing said releasable means, an auxiliary switch device removably mounted on the outside of said housing, actuating means for said auxiliary switch device mounted on the inside of said housing and normally maintaining said auxiliary switch device in operative condition, and said actuating means being engaged by said releasable means and moved to a position to permit operation of said auxiliary switch device.

3. In a circuit breaker comprising a housing, a releasable member operable when released to effect automatic opening of said circuit breaker, trip means for effecting release of said releasable member, auxiliary switch means mounted on the outside of said housing, biasing means biasing said auxiliary switch means to an operative position, actuating means for said auxiliary switch means comprising a spring mounted on the inside of said housing normally engaging and holding said auxiliary switch means against the bias of said biasing means, and said actuating spring being engaged by said releasable member upon release thereof and moved to a position to permit said biasing means to operate said auxiliary switch means.

4. A circuit breaker comprising a housing, means releasable to cause automatic opening of said circuit breaker, trip means for effecting release of said releasable means in response to abnormal circuit conditions, an auxiliary switch mounted in said housing, biasing means normally biasing said auxiliary switch to an operative position, actuating means for said auxiliary switch normally restraining said auxiliary switch against the bias of said biasing means, and said actuating means being engaged by said releasable means upon release thereof and moved to a position to permit said biasing means to actuate said auxiliary switch.

5. A circuit breaker comprising a housing, means releasable to cause automatic opening of

said breaker, trip means for effecting release of said releasable means in response to abnormal circuit conditions, an auxiliary switch mounted on said housing, biasing means normally biasing said auxiliary switch to an operative position, actuating means for said auxiliary switch comprising a biased member mounted on said housing normally restraining said auxiliary switch against the bias of said biasing means, and said actuating means being engaged by said releasable means upon release thereof and moved against its bias to a position to permit said biasing means to actuate said auxiliary switch.

6. A circuit breaker comprising a housing of molded insulating material, a releasable member operable when released to effect automatic opening of said breaker, trip means for effecting release of said releasable member, an auxiliary comprising a casing mounted on said housing, separable contact in said casing biased closed, actuating means for said auxiliary switch mounted on said housing and normally holding said separable contacts open, said releasable member when released engaging and moving said actuating means to permit said separable contacts to close.

7. A circuit breaker comprising a housing of molded insulating material, a releasable member operable when released to effect automatic opening of said breaker, trip means for effecting release of said releasable member, an auxiliary switch comprising a casing removably mounted on said housing, separable contacts in said casing biased closed, actuating means for said auxiliary switch comprising a spring mounted on said housing and normally holding said separable contacts open, said releasable member when released engaging and moving said actuating means to permit said separable contacts to close.

8. A circuit breaker comprising a housing of molded insulating material, operating means comprising a member releasable to effect automatic opening of said breaker, trip means responsive to overload circuits for releasing said releasable member, a manual lever for opening and closing said breaker and operable to reset said releasable members, an auxiliary switch comprising a casing mounted on said housing, auxiliary contacts in said casing, a resilient switch member in said casing biasing said auxiliary contacts to closed position, actuating means for said resilient switch member comprising a spring normally holding said resilient switch member in open position, said releasable member when released engaging and moving said actuating means to permit said resilient switch member to close said auxiliary contacts, and said actuating means upon resetting of said releasable member moving said resilient switch member to open said auxiliary contacts.

9. A circuit breaker comprising a housing of molded insulating material, operating means comprising a member releasable to effect automatic opening of said breaker, trip means responsive to overload circuits for releasing said releasable member, a manual lever for opening and closing said breaker and operable to reset said releasable member, an auxiliary switch comprising a casing removably mounted on the outside of said housing, auxiliary contacts in said casing, a resilient switch member in said casing biasing said auxiliary contacts to closed position, actuating means for said resilient switch member comprising a spring mounted on the inside of said housing and normally holding said

resilient switch member in open position, said releasable member when released engaging and moving said actuating means to permit said resilient switch member to close said auxiliary contacts, and said actuating means upon resetting of said releasable member moving said resilient switch member to open said auxiliary contacts.

10. A circuit breaker comprising means releasable to effect automatic opening of said breaker, trip means for releasing said releasable means, means for resetting said releasable means, auxiliary contact means comprising a resilient switch member biasing said auxiliary contact means to closed position, an actuator for said resilient switch member comprising a spring stronger than said resilient switch member disposed to normally hold said resilient switch member in open position, said releasable means when released engaging and moving said spring to permit said resilient switch member to close said auxiliary contacts, and said spring moving said resilient switch member to open position when said releasable member is reset.

11. A circuit breaker comprising an enclosing housing including a base and cover, operating means releasable to cause automatic opening of said breaker and trip means responsive to overload currents for effecting release of said releasable operating means and automatic opening of said breaker, all mounted on said

base, auxiliary switch means mounted on the outside of the cover portion only of said enclosing housing, and actuating means for said auxiliary switch means mounted on the inside of the cover portion only of said housing and engageable by said releasable operating means to effect operation of said auxiliary switch means.

12. A circuit breaker comprising a housing including a base and cover of molded insulating material, a releasable member operable when released to effect automatic opening of said breaker, trip means for effecting release of said releasable member, an auxiliary switch comprising a casing mounted solely on the cover portion of said housing, separable contacts in said casing biased closed, actuating means for said auxiliary switch mounted solely on the cover portion of said housing and normally holding said separable contacts open, said releasable member when released engaging and moving said actuating means to permit said separable contacts to close.
